United States Patent Office

Des. 182,531
Patented Apr. 15, 1958

182,531

CAMERA

Rudolf Müller, Jena, Germany

Application November 29, 1954, Serial No. 33,314

Claims priority, application Germany September 27, 1954

Term of patent 14 years

(Cl. D61—1)

Fig. 1.

Fig. 2.

Fig. 3.

Figure 1 is a perspective view of the camera showing my new design,

Fig. 2 is a rear side elevation thereof, and

Fig. 3 is an end view of the camera.

Portions of the drawing figures are stippled to indicate contrast in appearance.

I claim:

The ornamental design for a camera, as shown and described.
